EDGE GRINDING APPARATUS

Henry J. Hamann and Carl B. Williams, Jr.,
 Toledo, Ohio, assignors to Libbey-Owens-Ford
 Glass Company, Toledo, Ohio, a corporation of
 Ohio

Application August 18, 1938, Serial No. 225,500

8 Claims. (Cl. 51—96)

The present invention relates broadly to grinding machines and more particularly to improved apparatus for treating the edges of sheets or plates of glass and the like.

5 An object of this invention resides in the provision of grinding apparatus of relatively simplified and inexpensive construction particularly adapted for rounding the relatively sharp corners of sheets or plates of glass which are to be used 10 as door and window lights in automotive vehicles, although it is of course in no way restricted to such use.

Another object of the invention is the provision 15 of grinding apparatus of the above character which will round and finish the corners of the glass sheets or plates rapidly, accurately, and economically with a minimum amount of handling and also with a minimum amount of effort and attention on the part of the operator, whereby uniformly rounded corners with well finished 20 surfaces may be secured.

Another object of the invention is the provision 25 of grinding apparatus of the above character embodying a vertical grinding wheel rotatable about a substantially horizontal axis, a work holder rockably mounted above the grinding wheel for supporting the glass sheets to be ground on edge in a substantially vertical position, and means for rocking said work holder first in one direction 30 and then the other and for automatically varying the speed of rocking movement of the said work holder when it reaches predetermined positions to obtain a more efficient, uniform grinding 35 of the sheet edges.

35 Another object of the invention is the provision 40 of means for rocking the work holder in a manner to cause the same to move at a predetermined speed at the beginning and end of its rocking movement in either direction and to automatically slow down during the intermediate period 45 of its rocking movement so as to obtain a more intensive grinding action at the corners of the glass sheets where the maximum amount of material must be removed to effect the desired rounding thereof.

45 A further object of the invention is the provision 50 of means associated with the drive means for the work holder which will effect a more steady, even and uniform rocking movement thereof as well as causing it to be brought to an abrupt stop 55 immediately upon a shutting off of the driving power.

A still further object of the invention is the provision 55 of means associated with the work holder for facilitating the removal of the glass

sheets therefrom upon the completion of the grinding operation.

Other objects and advantages of the invention will become more apparent during the course of the following description, when taken in connection with the accompanying drawings.

In the drawings, wherein like numerals are employed to designate like parts throughout the same:

Fig. 1 is a side elevation of grinding apparatus 10 constructed in accordance with the invention;

Fig. 2 is a vertical section through the drive means for the work holder taken substantially on line 2—2 of Fig. 1;

Fig. 3 is a longitudinal vertical section through 15 the work holder;

Fig. 4 is a vertical section taken substantially on line 4—4 of Fig. 3;

Fig. 5 is a horizontal detail section taken substantially on line 5—5 of Fig. 3;

Fig. 6 is a horizontal detail section of the drive means for the work holder taken substantially on line 6—6 of Fig. 2;

Fig. 7 is a section through the friction brake means associated with the drive shaft taken substantially on line 7—7 of Fig. 2;

Fig. 8 shows a glass sheet having a relatively sharp corner to be rounded; and

Fig. 9 shows the sheet after being ground.

Referring now to the drawings, the grinding 30 apparatus comprises a suitable supporting framework 10 carrying at its upper end a horizontal channel member 11 comprising a bottom 12 and vertical side walls 13 and 14. Also mounted upon the supporting frame work 10 is a vertically disposed grinding wheel 15 rotatable about a substantially horizontal axis. The lower portion of the grinding wheel operates within a receptacle 16 containing a suitable abrasive material, while the upper portion of said wheel projects upwardly 40 through a slot 17 formed in the bottom 12 of channel member 11, as best shown in Fig. 3. Supported within the channel member 11, to one side of the grinding wheel, is a channel iron 18 carrying a plurality of freely rotatable horizontally 45 aligned conveyor rollers 19 over which the glass sheets may be moved to grinding position.

Mounted above the grinding wheel 15 is the work holder 20 adapted to support one or a plurality of glass sheets 21 to be treated. The work 50 holder 20 comprises the two spaced parallel, substantially L-shaped side members 22 and 23, each having a substantially vertical leg 24 and a substantially horizontal and relatively longer leg 25. Extending between and carried by the horizontal 55

legs 25 of the side members are a plurality of transverse pins 26 carrying the freely rotatable rollers 27 preferably grooved and adapted to receive the bottom edges 28 of the glass sheets 21 therein. Carried by and extending between the vertical legs 24 of said side members are one or more transverse pins 29 carrying freely rotatable grooved rollers 30 adapted to receive the inner edges 31 of the glass sheets 21. The vertical legs 24 of the opposite side members 22 and 23 of the work holder can be secured together at their outer ends by a transverse angle iron 32, while the horizontal legs 25 can be connected together at their outer ends by a similar angle iron 33.

Carried by the opposed vertical legs 24 of the side members 22 and 23, adjacent the outer ends thereof, are the substantially horizontal bracket arms 34 and 35 connected together at their outer ends by a transverse angle iron 36. Extending between and carried by the bracket arms 34 and 35 are the transverse pins 37 carrying the freely rotatable grooved rollers 38 adapted to receive the upper edges 39 of the glass sheets 21. The bracket arms 34 and 35 are adjustably secured to the side members 22 and 23 by means of bolts 40 passing through vertical slots 41 in said bracket arms whereby they may be raised or lowered to take care of glass sheets of different widths.

The work holder 20 is rockably mounted upon the channel member 11 and to this end, there is provided at substantially the juncture of the vertical and horizontal legs 24 and 25 the outwardly projecting trunnions 42 and 43 which are loosely received within vertical slots 44 and 45 in the side walls 13 and 14 respectively of said channel member. The trunnions 42 and 43 may be held against vertical movement within said slots by metal strips 46 and 47 secured to the vertical side walls 13 and 14 of channel member 11.

The side members 22 and 23 of work holder 20 may also be braced by the angle straps 48 secured to the vertical and horizontal legs 24 and 25. Pivotedly connected to said straps, intermediate the ends thereof, as at 49, are the substantially horizontal arms 50 and 51, said arms being connected together at their outer ends by a cross member 52 formed with a threaded socket 53. Threaded within the socket 53 is one end of a connecting rod 54 pivoted at its outer end as at 55 to the upper end of the vertical arm 56 of a bell-crank lever 57. The bell-crank lever 57 also has a substantially horizontal and relatively shorter arm 58 and is pivoted as at 59 to a bracket 60 carried by a supporting frame 61.

The means for rocking the bell-crank lever 57 to effect substantially horizontal reciprocating movement of the connecting rod 54 to cause rocking movement of the work holder 20 upon trunnions 42 and 43 comprises a rotatable cam 62, said cam being disposed in a vertical position and mounted upon a horizontal shaft 63 supported in a bearing 64 and driven from any suitable source of power such as an electric motor, not shown. The cam 62 has formed upon its outer face a continuous groove 65 of the desired shape and loosely received within said groove is a roller 66 carried at the lower end of a vertical slide block 67. This slide block is mounted for vertical sliding movement in a guide-way 68 provided in a channel member 69 secured to the supporting frame 61. Carried by the slide block 67, adjacent its upper end, is a pin 70 to which is pivoted one end of a vertical link 71 pivotally connected at its upper end, as at 72, to the arm 58 of bell-crank lever 57.

In the operation of the apparatus, the work holder 20 is first swung to the position shown in full lines in Fig. 1 at which time the rollers 27 thereof are in horizontal alignment with conveyor rollers 19 so that the glass sheets 21 to be treated can be moved horizontally over rollers 19 and 27 into the work holder and until the inner edges 31 thereof abut rollers 30. During the positioning of the glass sheets in the work holder, the cam 62 and its associated parts, including the roller 66, will also be in the positions indicated in Figs. 1 and 2. After the glass sheets have been properly positioned in the work holder 20, the drive shaft 63 is rotated to turn the cam 62 in a counter-clockwise direction as viewed in Fig. 1, whereupon the roller 66 running in the groove 65 of said cam will draw the slide block 67 downwardly. This will cause the bell-crank lever 57 to be rocked in a clockwise direction to swing the work holder 20 upon trunnions 42 and 43 also in a clockwise direction to move the lower inner corners of the glass sheets indicated at *a* in Fig. 8 over and in engagement with the grinding wheel 15. The groove 65 in cam 62 is so shaped that after the work holder has been turned approximately 90 degrees, the slide block 67 will be moved upwardly to rock the bell-crank lever 57 in a counter-clockwise direction to return the work holder to its original starting position. During the return movement of the work holder, the corners *a* of the glass sheets will also engage the grinding wheel. Ordinarily, the rocking of the glass sheets first in one direction and then back to starting position will be sufficient to properly grind the relatively sharp corners *a* of the said sheets so that they will be rounded as indicated at *b* in Fig. 9. The periphery of the grinding wheel 15 may be flat as shown or it may be provided with a plurality of circumferential grooves 40 to form a so-called pencil edge on the glass sheets.

In order to properly round the square corners *a* (Fig. 8) of the glass sheets, it is desirable that the speed of rocking movement of the work holder 20 be reduced during an intermediate period 45 of the grinding operation so that a more intensive grinding of the corners can be obtained where the greatest amount of glass must be removed. Therefore, according to the invention, the groove 65 in cam 62 is so shaped that as the 50 glass sheets 21 are rocked in a clockwise direction, the work holder 20 will move at a predetermined speed until the bottom edges 28 of the glass sheets are disposed substantially at an angle represented by the line *c* in Fig. 8. At this time, 55 the speed of rocking movement of the work holder will be increased to its original speed and this movement continued throughout the remainder of its travel. Upon the return of the work holder to its starting position, it will travel 60 at the relatively higher speed until the edges 28 of the glass sheets are disposed at the angle represented substantially by the line *d*, whereupon the speed of movement of the work holder will be reduced until the edges 28 are disposed at the 65 angle represented substantially by the line *c* at which time its speed of movement will again be increased and continued throughout the balance of the rocking movement of the work holder. By reducing the speed of rocking movement 70 of the work holder in this manner, it will be apparent that more time will be allowed for grinding those portions of the corners where the largest amount of material must be removed.

With the form of cam shown in Fig. 1, the work 75

- holder 20 will travel at its higher rate of speed during the movement of the roller 66 from the position therein shown to the point A in groove 65 while during the travel of the roller from point 5 A to point B the speed of rocking movement of the work holder will be reduced. As the roller 66 travels from point B to point C the speed of movement of the work holder will again be increased and when the roller 66 reaches point C 10 in groove 65 the work holder will have been turned in a clockwise direction approximately 90 degrees. As the roller 66 travels from point C to point D the work holder will be rocked in a counter-clockwise direction at its higher speed 15 whereas its speed of movement will be slowed down as the roller travels from point D to point E and then again increased upon travel of said roller from point E back to the position shown in Fig. 1.
- 20 When the work holder 20 reaches the end of its return movement, it is adapted to actuate a limit switch 73 to automatically shut off the motor driving the shaft 63. It is desirable to bring the drive shaft 63 to an abrupt stop upon 25 shutting off of the driving power thereto whereby to prevent any further movement of the work holder. For this purpose, there is associated with the drive shaft 63 a friction brake designated in its entirety by the numeral 74.
- 30 As best shown in Fig. 7, the shaft 63 has keyed thereto a brake drum 75, while encircling said drum are the two semi-circular brake shoes 76 and 77 hinged together at one end as at 78 upon a fixed bracket 79. Also encircling the brake 35 drum 75 within brake shoes 76 and 77 is the brake lining 80. The outer ends of the brake shoes 76 and 77 are provided with spaced ears 81 and 82 respectively and passing therethrough is an adjusting bolt 83 having a nut 84 threaded upon one end and a spring 85 encircling the opposite end outwardly of 81, said spring 85 normally urging the brake shoes towards one another and into engagement with the brake drum. Upon rotation of the bolt 83, the pressure exerted by the brake shoes upon the drum may 40 be varied as desired. In addition to bringing the shaft 63 to an abrupt stop upon shutting off of the motor which drives the same, the friction brake 74 also causes the shaft 63 and consequently the work holder to have a more steady 45 movement with less vibration which will result in a more even, uniform grinding of the sheet edges.
- The invention also includes means for facilitating the removal of the glass sheets 21 from the work holder 20 upon completion of the grinding thereof. This means includes a pair of arms 86 and 87 arranged outwardly of the side members 22 and 23 of the work holder and pivotally 50 mounted at their inner ends upon the reduced inner end portions 88 and 89 of the trunnions 42 and 43 respectively. The arms 86 and 87 are connected together at their outer ends by the transverse member 90 which forms a hand-grip 55 for the operator to facilitate swinging movement of said arms upon said trunnions. Carried by the arms 86 and 87 intermediate the opposite ends thereof are the bracket plates 91 and 92 respectively and arranged between and carried by said bracket plates is a roller 93. This roller is adapted, during the grinding of the glass sheets, to be received between the side members of the work holder and engageable by the inner edges 31 of the glass sheets. As best 60 shown in Fig. 5, the bracket plates 91 and 92 are received within the vertical legs 24 of the side members 22 and 23 of the work holder and are adapted to frictionally engage the inner surfaces of the said legs and held thereby in position until manually disengaged therefrom by the 65 operator. As before stated, during the grinding of the glass sheets, the roller 93 engages the inner edges of the glass sheets as shown in full lines in Fig. 3 at which time the arms 86 and 87 will be in the dotted line position. After 70 the grinding operation has been completed and it is desired to remove the glass sheets from the work holder, the operator simply grasps the transverse member 90 and pushes the same rearwardly thereby swinging the arms 86 and 87 forwardly to the position indicated by the dot and dash lines in Fig. 3. As the arms are swung forwardly to this position, the roller 93, engaging the inner edges of the glass sheets, will shove the sheets rearwardly to partially eject them 75 from the work holder and into a position where they can be more readily removed from the work holder by the operator.
- It is to be understood that the form of the invention herewith shown and described is to 25 be taken as the preferred embodiment of the same, and that various changes in the shape, size and arrangement of parts may be resorted to without departing from the spirit of the invention or the scope of the subjoined claims. 30
- We claim:
1. An apparatus for rounding the relatively sharp corner of a sheet or plate of glass or the like, a rotary grinding wheel positioned to rotate about a substantially horizontal axis, a work 35 holder mounted above the grinding wheel for supporting the sheet to be ground on edge in a substantially vertical position, and means for rocking said work holder first in one direction and then the other to move the corner of the 40 sheet to be rounded over and in engagement with said grinding wheel, said means including means for causing said work holder to travel relatively fast at the beginning and end of its rocking movement and relatively slower during the 45 intermediate period of its rocking movement.
  2. An apparatus for rounding the relatively sharp corner of a sheet or plate of glass or the like, a rotary grinding wheel positioned to rotate about a substantially horizontal axis, a work 50 holder mounted above the grinding wheel for supporting the sheet to be ground on edge in a substantially vertical position, and means for rocking said work holder first in one direction and then the other to move the corner of the 55 sheet to be rounded over and in engagement with said grinding wheel, said means including cam means for causing said work holder to travel relatively fast at the beginning and end of its rocking movement and relatively slower during 60 the intermediate period of its rocking movement.
  3. An apparatus for rounding the relatively sharp corner of a sheet or plate of glass or the like, a rotary grinding wheel positioned to rotate about a substantially horizontal axis, a work 65 holder mounted above the grinding wheel for supporting the sheet to be ground on edge in a substantially vertical position, and means for rocking said work holder first in one direction and then the other to move the corner of the 70 sheet to be rounded over and in engagement with said grinding wheel, said means including rotatable cam means constructed to cause said work holder to travel relatively fast at the beginning and end of its rocking movement and 75

relatively slower during the intermediate period of its rocking movement.

4. An apparatus for rounding the relatively sharp corner of a sheet or plate of glass or the like, a rotary grinding wheel positioned to rotate about a substantially horizontal axis, a work holder mounted above the grinding wheel for supporting the sheet to be ground on edge in a substantially vertical position, means for rocking 5 said work holder first in one direction and then the other to move the corner of the sheet to be rounded over and in engagement with said grinding wheel, a rockably mounted arm carried by said work holder, and a roller carried by said arm engaging the inner edge of the glass sheet and adapted upon rocking of the said arm upon completion of the grinding operation to eject the glass sheet from the said work holder.
5. An apparatus for rounding the relatively sharp corner of a sheet or plate of glass or the like, a rotary grinding wheel positioned to rotate about a substantially horizontal axis, a work holder mounted above the grinding wheel for supporting the sheet to be ground on edge in a substantially vertical position, means for rocking 10 said work holder first in one direction and then the other to move the corner of the sheet to be rounded over and in engagement with said grinding wheel including a drive shaft, a cam carrier thereby, operative drive connections between 15 said cam and work holder, said cam being constructed to cause said work holder to travel relatively fast at the beginning and end of its rocking movement and relatively slower during the intermediate period of its rocking movement, and 20 braking means associated with said drive shaft for bringing the same to an abrupt stop upon shutting off of the driving power thereto.

6. An apparatus for rounding the relatively sharp corner of a sheet or plate of glass or the like, a rotary grinding wheel positioned to rotate about a substantially horizontal axis, a work holder mounted above the grinding wheel for supporting the sheet to be ground on edge in a substantially vertical position, means for rocking 25 said work holder first in one direction and then the other to move the corner of the sheet to be rounded over and in engagement with said grinding wheel, and means carried by said work holder and adapted to be manually actuated upon completion of the grinding operation for ejecting the glass sheet from the said work holder.
7. An apparatus for rounding the relatively sharp corner of a sheet or plate of glass or the like, a rotary grinding wheel positioned to rotate about a substantially horizontal axis, a work holder mounted above the grinding wheel for supporting the sheet to be ground on edge in a substantially vertical position, means for rocking 30 said work holder first in one direction and then the other to move the corner of the sheet to be rounded over and in engagement with said grinding wheel, and means pivotally carried by said work holder and adapted to be actuated upon completion of the grinding operation for ejecting the glass sheet from the said work holder.

8. An apparatus for rounding the relatively sharp corner of a sheet or plate of glass or the like, a rotary grinding wheel positioned to rotate about a substantially horizontal axis, a work holder mounted above the grinding wheel for supporting the sheet to be ground on edge in a substantially vertical position, means for rocking 35 said work holder first in one direction and then the other to move the corner of the sheet to be rounded over and in engagement with said grinding wheel, a pair of arms pivotally carried by said work holder, and a member arranged between 40 and carried by said arms engaging the inner edge of the glass sheet and adapted upon rocking of the said arms upon completion of the grinding operation to eject the glass sheet from the said work holder.
